INDOOR TABLE TOP TETHER BALL GAME STANDARD

Fred S. Anthony, Coos Bay, Oreg., assignor to Oregon
Novelties, Inc., Coos Bay, Oreg.

Filed Mar. 1, 1971, Ser. No. 119,998

Term of patent 14 years

Int. Cl. D21—01

U.S. Cl. D34—5

FIG. 1 is a perspective view of an indoor table top tether ball game standard embodying my new design;

FIG. 2 is a bottom view of such structure;

FIG. 3 is a fragmentary horizontal section taken along line 3—3 of FIG. 1; and

FIG. 4 is a fragmentary horizontal section taken along line 4—4 of FIG. 1.

I claim:

The ornamental design for an indoor table top tether ball game standard, as shown and described.
